(57) **CLAIM**

The ornamental design for a seat, as shown and described.

DESCRIPTION

FIG. 1 is a left front perspective view of a seat showing my new design;

FIG. 2 is a front perspective view thereof;

FIG. 3 is a side elevational view, the opposite side being a mirror image thereof;

FIG. 4 is a rear elevational view thereof; and,

FIG. 5 is a top view thereof.

The broken lines shown along the seams of the backrest are understood to represent stitching.

The bottom view of the seat is not shown and forms no part of the claimed design.
